COMBINED THERMOMETER AND REAR-
VIEW MIRROR FOR USE ON MOTOR
VEHICLES

Michael C. Vacanti, Irondequoit, N. Y., assignor
to Germanow-Simon Machine Company, Inc.,
Rochester, N. Y., a corporation of New York

Application July 23, 1949, Serial No. 4,103

Term of patent 7 years

(Cl. D14—6)

To all whom it may concern:

Be it known that I, Michael C. Vacanti, a citizen of the United States of America and resident of the town of Irondequoit, in the county of Monroe and State of New York, have invented a new, original, and ornamental Design for a Combined Thermometer and Rearview Mirror for Use on Motor Vehicles, of which the following is a specification, reference being had to the accompanying drawings, forming part hereof.

Fig. 1 is a front elevational view of a combined thermometer and rear view mirror, showing my new design;

Fig. 2 is a top plan view thereof;

Fig. 3 is a side elevational view thereof; and
Fig. 4 is a rear elevational view thereof.

I claim:

The ornamental design for a combined thermometer and rear view mirror for use on motor vehicles, substantially as shown.

MICHAEL C. VACANTI.
